UNITED STATES PATENT OFFICE.

JAMES R. CARDWELL, OF CHICAGO, ILLINOIS, ASSIGNOR TO UNION DRAFT GEAR COMPANY, A CORPORATION OF ILLINOIS.

DRAFT AND BUFFING MECHANISM.

1,182,143.

Specification of Letters Patent.

Patented May 9, 1916.

Application filed June 7, 1915. Serial No. 32,604.

To all whom it may concern:

Be it known that I, JAMES R. CARDWELL, a citizen of the United States, and a resident of Chicago, county of Cook, and State 5 of Illinois, have invented certain new and useful Improvements in Draft and Buffing Mechanism, of which the following is a specification, and which are illustrated in the accompanying drawings, forming a part 10 thereof.

The invention relates to mechanism for transmitting draft and buffing stresses to the framework of a car, and particularly to devices of this character in which a supplemental buffing element is present.

The objects of the invention are to simplify and increase the efficiency of such structures, and to provide holding means for the supplemental buffing element.

20 In the drawings illustrating an embodiment of the invention, Figure 1 shows a detail plan view of a portion of the framework of a car, with the improved device applied thereto, some portions being broken away; 25 and Fig. 2 is a longitudinal vertical section taken inside of one of the car sills, the draft lugs associated with such sill not being shown.

30 The center or draft sills of a car are shown at 10, 11, and to each of such sills is affixed a draft lug 12 and a buffing lug 13. The shank of a coupler is represented at 14, and as being provided with an extension or yoke 15 of the ordinary loop type. The 35 draft gear or cushioning device is inclosed within the yoke 15, and may be of any preferred construction, there being shown the well-known Cardwell friction gear comprising a pair of followers 16, 17, having a 40 box or casing form, and inclosing between them friction elements, shown mainly in dotted lines and generally designated by the numeral 18, and a transverse rod 19 extending through the sills and carrying upon its 45 ends springs 20, 21.

The supplemental buffing mechanism is shown as of the same construction, its followers being designated by the numerals 22, 23. The rearward follower is in engagement 50 with the buffing lugs 13, and the forward follower is in butting engagement with the rearward follower 17 of the draft gear.

A yoke 24, in loop form, incloses the buffing gear, and for convenience of manufacture and assembling this loop may com-

prise a U-shaped element and an end plate 25 uniting the ends of such element, and being secured thereto by any suitable means, as rivets, as shown.

The contiguous faces of the followers 17 60 and 23 are recessed to accommodate the ends of the yokes 15 and 24, and to provide clearance for the backward movement of the yoke 15 in buffing. The yoke 24 holds the elements of the buffing gear together and 65 prevents its undue expansion. The yoke 15 performs the same office with reference to the draft gear, and consequently when the device is assembled and at rest there is no expansive pressure of the one gear upon the 70 other, each, however, holding the other in place in co-operation with the draft and buffing lugs between which as a whole the parts snugly fit.

Under draft stresses the yoke 15 and with 75 it the follower 17 move forward and away from the follower 23. Any suitable means may be provided for preventing the buffing gear from moving forward at such time due to jarring influences. In the device as 80 shown such movement is prevented by the engagement of the bar 26 of the buffing gear with the forward ends of the slots 27 in the sills through which it passes.

Buffing stresses are transmitted from the 85 coupler through both sets of gears and the lugs 13 to the sills. The compression of the forward gear in this case causes the yoke 15 to move backward a greater distance than the follower 17, and the recesses in this follower and the follower 23 provide the necessary clearance for the end of the yoke in this action. As the supplemental buffing gear is compressed its yoke 24 may move backward, and will be forced backward in 90 extreme cases by contact with its forward end of the rearward end of the yoke 15.

I claim as my invention—

1. In a device of the kind described, in combination, a draft gear and a buffing gear 100 each comprising a pair of followers, such gears being arranged in tandem and having their adjacent followers normally in contact, such followers having their contiguous faces recessed, and a yoke inclosing the draft 105 gear, its rearward end occupying the recess in the follower thereof.

2. In a device of the kind described, in combination, a draft gear and a buffing gear each comprising a pair of followers, such 110

gears being arranged in tandem and having their adjacent followers normally in contact, such followers having their contiguous faces recessed, and a yoke inclosing the buffing gear and being in the form of a closed loop.

3. In a device of the kind described, in combination, a pair of tandem arranged buffing gears each comprising end members and intermediate stress-absorbing elements, the adjacent end members of the two gears

being normally in contact and each having its outer face recessed, a loop inclosing each gear and fitting loosely within the recesses of such end members, a pair of draft shoulders, coöperating with the forward end of the forward gear, and a pair of buffing shoulders coöperating with the rearward end of the rearward gear. ¹⁵

JAMES R. CARDWELL.
